UNITED STATES PATENT OFFICE.

CLARENCE E. FORT AND AUGUSTUS S. HORTON, OF ROCKFORD, ILLINOIS.

WIND-SHIELD AND PROTECTOR FOR CIGARS.

1,240,329.

Specification of Letters Patent. Patented Sept. 18, 1917.

Application filed April 20, 1916. Serial No. 92,406.

To all whom it may concern:

Be it known that we, CLARENCE E. FORT and AUGUSTUS S. HORTON, citizens of the United States, residing at Rockford, in the 5 county of Winnebago and State of Illinois, have invented certain new and useful Improvements in Wind-Shields and Protectors for Cigars, of which the following is a specification.

- 10 This invention has reference to means for shielding and protecting the lighted end of a cigar when smoking out in the open and in windy weather, and especially when motoring. In the latter instance the rush of 15 air incidental to the fast movement of the car causes the cigar to burn unevenly and too rapidly so that the duration and enjoyment of the smoke is materially decreased. Furthermore, the flying about of 20 sparks and ashes from the cigar are a source of danger and annoyance to others in the vicinity of the smoker.
- Prior to our invention various means have been contemplated to shield or protect in 25 some way the lighted end of a cigar, but so far as we are aware, they have been inadequate for the purpose and commercially unsuccessful. Some of the objectionable features inherent in prior devices may be traced 30 to their construction which renders cost of production prohibitive, to heating of the shield without proper provision for adjusting or handling of the same, to unsightly appearance, and what is most important, to 35 improper and in some instances, no provision for circulation of air within the shield which is essential to support uniform and normal combustion under all conditions of usage.
- 40 Our invention aims, primarily, to provide a cigar shield and protector which will most effectively protect the cigar and promote the enjoyment of a smoker when motoring or out in the open and which will be devoid 45 of the disadvantages and objectionable features mentioned.

Our invention also contemplates the provision of an article of this character that may be economically produced and sold at a 50 comparatively low price.

To these ends we have designed a shield or protector of novel construction characterized generally by the provision of a bullet-shaped cap or shell of light non-combustible 55 material adapted to fit over the lighted end

of a cigar and provide uniform air space entirely about the cigar, the shell being imperforate except for a plurality of apertures arranged so as not to allow air to enter the shield from the front thereof or in a 60 manner to interfere with normal combustion, but to permit free ingress of such air as is drawn in by the smoker so as to allow perfect circulation within the shield to support normal combustion and permit smoke 65 to escape freely from the shell. Our invention also contemplates the provision of means for detachably and adjustably securing the shell to the lighted end of a cigar, said means being constructed so as to be 70 substantially insulated from the shell and readily accessible for the purpose of attachment to and detachment from a cigar and to enable the shell to be adjusted farther back on the cigar as the same is burned. 75

These features and other attendant advantages will become better understood by reference to the following specification when considered in connection with the accompanying drawing in which we have illustrated one embodiment of our invention, and in which—

Figure 1 is a side view of a cigar shield and protector embodying our improvements; Fig. 2 is a view looking at the open end 85 of the shield;

Fig. 3 is a longitudinal sectional view taken on the line 3—3 of Fig. 1; and

Fig. 4 is a perspective view of the cigar-attaching means removed from the shield. 90

Referring to the drawings, the body of the wind shield designated generally by reference character 5, is of a general conical or bullet shape so as to provide a shell closed and imperforate at its pointed end 6 and open at its opposite end 7 to receive the lighted end of a cigar. This shell may be formed of any suitable non-combustible light weight material, it being preferably 95 pressed or drawn from aluminum. 100

We have provided novel means for attaching the shell to a cigar so as to position the same centrally within the shell to provide a substantial air space entirely about the incased end of the cigar. This fastening means in its preferred form consists of a spring wire section bent upon itself providing a portion 8 secured to the shell at the inner side thereof, the said portion 8 being in the present instance confined between a 110

punched-out portion 9 of the shell and the adjacent inner wall portions thereof. The two end portions of the wire are twisted together at 11, extended beyond the open end 5 of the shell and turned in opposite directions in a plane at right angles to the axis of the shell to form cigar-embracing portions 12 intermediate the ends of which are formed forwardly projecting offsets 13 and 10 then crossed and turned outwardly away from the cigar and shaped to provide finger pieces 14 disposed beyond the perimeter of the shell.

The shell may be easily positioned on a 15 cigar by grasping the outer sides of the finger pieces 14 between the thumb and forefinger, pressing these finger pieces together against the tension of the spring wire so as to spread the cigar-engaging portions 12 for the reception of a cigar, and then adjusting the shell on the cigar so that the lighted end thereof is positioned centrally within and adjacent to the nose of the shell, whereupon when the finger pieces 20 are released the shell will be secured in fixed relation to the cigar through the intermediary of the resilient arms. It will be noted that these arms being of comparatively small size stock and secured to the shell at but a single point and disposed in 25 spaced relation therefrom are substantially insulated from the shell so that should the shell become heated from the burning cigar the finger pieces remain cool, consequently 30 the shell may be conveniently handled and adjusted at all times. The portions 13 of the fastening means extending in a plane parallel with the axis of the shell serve to maintain the cigar in axial alinement with 35 the shell. By positioning the cigar-engaging portions of the fastening means in spaced relation to the rear of the open end of the shell, the smoker is enabled to easily 40 note when it is necessary to adjust the shell 45 farther back on the cigar. It will be further observed that an unobstructed air space is provided within the shell entirely about the cigar so that with the provision of certain perforations in the shell, free 50 circulation and normal combustion may be maintained within the shell.

In order to provide for normal combustion within the shell under all circumstances and yet prevent air currents from entering 55 and interfering with such combustion, we have perforated the shell in a novel manner. These perforations are, in fact, shielded openings arranged circumferentially about the shell so as to allow air to be freely drawn 60 into the shell during the act of smoking and to permit escape of smoke from the shell. These shielded openings also prevent air currents not drawn by the smoker, that is, such currents as are caused when motoring by the 65 rush of air striking against the nose 6 of the

shell, from entering the shell. In the present instance, the imperforate nose 6 serves to effectively deflect air striking the same, outwardly and away from the shell. The shell at the rear of its imperforate nose portion 70 is pierced at a plurality of circumferentially spaced points 15 and the portions at the rear thereof are depressed as at 16 so as to provide apertures 17, which open toward the rear of the shell and the entrances to which 75 are shielded by the imperforate nose 6. It will be apparent that by perforating the shell in this manner the lighted cigar is effectively shielded against abnormal air currents and at the same time provision is made 80 for permitting free ingress of air to the shell adjacent to the lighted end of a cigar by the act of smoking. The shell is also perforated over a portion of its top by a plurality of small apertures 18, these perforations serving to permit escape of smoke through the top of the shell so that the smoke will not be deflected backwardly into the face of the smoker as might occasionally occur in case 85 no top perforations were provided. In this 90 connection it will be noted that there are no side perforations other than the shielded openings 17 so that lateral air currents striking the sides of the shell can not enter the same.

We have also provided means disposed within the nose of the shell against which a match inserted through one of the apertures 95 17 may be rubbed and ignited to light the cigar. This means consists of a suitable element 19 secured to the shell within the nose thereof, as shown in Fig. 3, provided with a roughened surface such as a fine wire mesh presents, so that sufficient friction may be caused by a slight rubbing movement of a 100 match head thereagainst to ignite the match. By the provision of such means the smoker is enabled to light a cigar without any difficulty or possibility of a match being blown out by the wind.

From the foregoing, it will be manifest that by means of our improvements the shell offers but little resistance to the wind and effectively deflects the same and prevents entrance of any abnormal air currents which 115 might interfere with normal combustion within the shell, that the shell serves as a spark arrester and ash collector, and by reason of the novel perforating of the shell and manner in which the cigar is supported 120 within the same an atmospheric condition is maintained within the shell similar to and suitable for supporting combustion as when smoking under normal conditions regardless of the atmospheric conditions exterior of the 125 shell, and that the shell may be easily and conveniently adjusted on the cigar without danger of burning the hand.

It is believed that the construction, operation and many advantages of our invention 130

will be understood from the foregoing without further description, and the invention is not limited by the structural details disclosed, all of which are capable of considerable modification within the scope of the invention as defined by the following claims.

We claim:

- 10 1. A shield or protector for cigars comprising a conically shaped shell adapted to receive the lighted end of a cigar, and means for detachably securing a cigar to and centrally within the shell so as to allow a circumferential air space entirely about the incased portion of the cigar, the closed end of the shell being imperforate and the shell being formed intermediate its ends with circumferentially spaced openings shaped so
- 15

as to open toward the rear or open end of the shell.

2. A shield or protector for cigars comprising a shell shaped to receive the lighted end of a cigar, means for detachably securing a cigar to and centrally within the shell, said shell being imperforate except for openings arranged circumferentially about the shell in proximity to the closed end thereof and shaped so as to open toward the rear or open end thereof, and other openings at the top only of the holder and rearwardly of said circumferentially spaced openings through which smoke may pass from the shell.

CLARENCE E. FORT.
AUGUSTUS S. HORTON.
